UNITED STATES PATENT OFFICE

EDGAR ROUSE SUTCLIFFE, OF LEIGH, ENGLAND

DISTILLATION OF CARBONACEOUS SUBSTANCES

Application filed July 16, 1924, Serial No. 726,294, and in Great Britain July 25, 1923.

The invention relates to the distillation of coal and similar carbonaceous substances and comprises the method and means employed.

- 5 According to the invention steam is decomposed for the production of combustible gas which in part is used for heating the charge to be distilled and in part is utilized for heating one of a pair of heaters, regenerators 10 or blast stoves (hereinafter called "heaters") that are alternately used for super-heating the steam before its admission to the charge. It will be understood that the steam is decomposed on contact with the incandescent 15 carbon and that water gas may be produced.
- According to the invention moreover the treatment is carried out in vertical retorts, and heaters advantageously provided in pairs for alternate use, are built in the same 20 setting and conveniently in position immediately beside the respective retorts; and beneath each heater a combustion chamber is provided within which part of the gas produced is burnt, whereby when one heater is 25 used for superheating the steam intended for use in the distillation, a part of the resulting gas flows up the retort through the charge therein for the purpose of applying heat thereto, whereby part of its sensible 30 heat is absorbed in the distillation of the volatile content, while another part of the resulting gas passes into the combustion chamber of the other heater where it is burnt, the products of combustion passing 35 upwardly through the heater whereby it is heated. After a determined period the temperature of the heater through which the steam has been passed for super-heating it, will have reached a low degree while the 40 other heater of the pair will have been raised to a high temperature. The steam will then be cut off from the cooled heater and passed through that which has been heated. At the same time part of the resulting gas produced 45 as described will then be burnt in the combustion chamber beneath the cooled heater, whereby the course of the steam and gas is thus reversed for a further determined period, the alternation continuing so long 50 as the retort is maintained in operation.

The invention comprises the features which are hereinafter described.

The invention is diagrammatically illustrated in the accompanying drawing which illustrates a retort setting constructed for 55 use according to the invention.

In the drawing Figure 1 is a vertical section.

Figure 2 is a horizontal transverse section on the line 2-2 Figure 1, in which one 60 heater is shown filled with reticulated brick-work.

Figure 3 is a horizontal transverse section on the line 3-3 Figure 1, and

Figure 4 is a horizontal transverse section on the line 4-4 Figure 1.

In the drawings one unit alone is illustrated, and this may be contained in an independent setting, or as is preferred a number of vertical retorts are advantageously 70 arranged in line in the same setting, and pairs of heaters disposed one at each side of each retort in the manner illustrated in the drawing.

In carrying the invention into effect as 75 illustrated in the accompanying diagrammatic drawing, a number of vertical retorts *a* are advantageously provided in the same setting, and these retorts are conveniently provided of an oblong cross-sectional shape, 80 with the major axes of the cross-sections in line; and the retorts *a* may advantageously be provided of firebrick. The retorts are advantageously tapered outwardly towards the bottom. The heaters *b* *b*¹ are provided 85 in pairs and of a width substantially co-extensive with the respective retorts with no intermediate brickwork between, so that thus heat is directly transmitted from the heaters *b* *b*¹ to the parallel oppositely disposed walls of the retort. The lower end of the retort is carried by firebrick *c* which bridges over a cavity formed by two parallel vertical walls beneath the pair of heaters. Immediately beneath the retorts a receptacle 90 *d* is formed in the brickwork of which the lower part *d* of the setting is made, and this takes a form corresponding to the lower end of the retort, but its upper part is flared outwardly at *d* so that thus in operation the 100

charge may accumulate in position between the bridge *c* and the receptacle *l* in the lower part *d* of the setting, wherein the charge may be to a certain extent cooled before its periodic discharge. Beneath the heaters *b* 5 *b*¹, combustion chambers *e* *e*¹ are provided and in position between the vertical walls of the combustion chambers *e* *e*¹, brickwork *f* is provided in which air holes *g* are formed which open out on the inclined faces *f*¹ of 10 the brickwork, so that thus narrow spaces *h* intervene between the brickwork *f* and the bridge *c*, through which gas may pass from the charge and may be burnt in the combustion chamber *e* or *e*¹ on the admission of air through the air holes *g*.

The heaters may be provided of the usual reticulated brickwork and spaces of ample area are formed in the lower part of the heaters *b* *b*¹ through which the flames and 20 gases from the combustion chambers *e* *e*¹ may pass to the heaters or through which steam from the heaters may pass to the combustion chambers. Steam is led into the heaters through the steam inlet *k* or *k*¹, 25 while a waste gas outlet (not indicated in the drawing) is also provided for each heater.

A gas off-take fitting *i* is mounted at the 30 top of the retort, and a gas off-take pipe is connected to this fitting by which the gas and vapour may be led into the hydraulic main; and above the fitting *i* is disposed a hopper fitting *j* through which the coal or 35 other carbonaceous substance may be fed into the retort.

In operation it will be understood that the charge is periodically fed to the retorts *a* and is periodically withdrawn. The steam admitted at *k*¹ into the heater *b*¹ passes 40 downwardly and is raised to a high temperature, for example to a temperature of 850° C. It then passes through the combustion chamber *e*¹, through the space *h* into the charge accumulating beneath the lower end 45 of the retort. The steam thus superheated, passes through the accumulation of fuel beneath the retort *a*, and a combustible gas is produced by its decomposition in reaction, 50 and part of this combustible gas passes up through the charge of fuel in the retort, imparting its sensible heat to the charge, and thus effecting its distillation, the vapour and gas passing outwardly through the 55 gas off-take pipe, together with any residual steam that may not have been decomposed.

Another part of the combustible gas produced passes out into the combustion chamber *e*, and in passing through the narrow 60 space *h* is burnt with air passing in through the air holes *g*. Thus the flame and hot gases pass upwardly into the heater *b*. After a determined period, for example 30 minutes, the heater *b* will have been heated to a 65 sufficiently high temperature, and the heater

*b*¹ will have been cooled, whereupon the supply of steam may be cut off from the heater *b*¹ and be admitted to the heater *b*. The waste gas outlet of the heater *b* is simultaneously closed, and the waste gas outlet of the heater *b*¹ is opened, whereupon a complete 70 reversal of the operation may be carried out for a further period, and thus the operations may be alternately repeated, while the charge is periodically or continuously withdrawn through the outlet fitting *m*.

No limitation is involved to the particular temperature conditions that may be used. Where for example it is desired to produce a maximum quantity of oils and tar from 80 coal, the distillation may be carried out at a low temperature such for example as 750° C., and an excess of steam used; whereas if a maximum gas production is desired the distillation may be carried out for example to 1200° C., and such a quantity of steam admitted as can be readily decomposed; while if a high yield of oils and tar and a high yield of gas are desired the process may be carried out at a high temperature with 85 excess of steam.

It will be understood that gas may be admitted with the steam, whereby the distillation may be carried out in the same manner as hereinbefore described; or combustible gas alone may be used, the gas being admitted alternately through the respective heaters, instead of steam.

The method and apparatus of the invention may be used for the distillation of coal which has been reduced to a uniform condition of extreme fineness and compressed into stonelike blocks or pieces without the necessary use of a binder, that is to the coking of blocks produced according to the process of the prior Patent No. 1,267,711 by subjecting such blocks to the process of the prior Patent No. 1,261,645; or the method and apparatus may be used for carrying out the treatment of distillation for the production of absorbent or contact material according to the prior application No. 354,468, or otherwise for the distillation of coal and other similar solid carbonaceous substances, in substitution of the method and apparatus usually employed.

It will be understood that the duration of the distillation, that is to say the rate of discharge, will be determined according to the character of the carbonaceous substance to be distilled and if desired according to any particular degree.

Furthermore instead of pairs of heaters being provided for each retort, pairs or other number of heaters may be used for more than one retort without departing from the invention, but no claim is made broadly to the use of pairs of heaters.

I claim:

1. An apparatus for the distillation of 130

- coal and similar carbonaceous substances, comprising in combination within a setting, of a substantially vertical retort, two chequered blast stoves one at each side of the
 5 said retort, means by which hot gas may be passed through one of the said chequered blast stoves alternately and means by which a gaseous medium may be passed through the other of the said chequered blast stoves
 10 alternately and into the said retort, the said setting also having combustion chambers respectively beneath each of the said chequered blast stoves, the said combustion chambers being in communication with the said
 15 respective chequered blast stoves and with the lower end of the said retort throughout both phases of the alternating cycle, the said combustion chambers serving alternately for the combustion of the said hot gas
 20 therein, substantially as hereinbefore described.
2. An apparatus for the distillation of coal and similar carbonaceous substances, comprising in combination within a setting, of a substantially vertical retort, two chequered blast stoves one at each side of the
 25 said retort, means by which hot gas may be passed through one of the said chequered blast stoves alternately and means by which
 30 a gaseous medium may be passed through the other of the said chequered blast stoves alternately and into the said retort, the said setting also having combustion chambers respectively beneath each of the said
 35 chequered blast stoves, the said combustion chambers being in communication with the said respective retort throughout both phases of the alternating cycle the said combustion chambers serving alternately for
 40 the combustion of the said hot gas therein, the said setting also having a space in communication with the combustion chambers throughout both phases of the alternating cycle beneath the said retort adapted to receive the incandescent charge on its issue from the lower end of the said retort, substantially as hereinbefore described.
3. An apparatus for the distillation of coal and similar carbonaceous substances, comprising in combination within a setting, of a substantially vertical retort, two chequered blast stoves one at each side of the
 50 said retort, means by which hot gas may be passed through one of the said chequered blast stoves alternately and means by which a gaseous medium may be passed through the other of the said chequered blast stoves alternately and into the said retort, the said setting also having combustion chambers respectively beneath each of the said chequered blast stoves, the said combustion chambers being in communication with the said respective chequered blast stoves and with the lower end of the said retort throughout both phases of the alternating cycle the said combustion chambers serving alternately for the combustion of the said hot gas therein, the said setting having a space in communication with the combustion chambers throughout both phases of the alternating cycle beneath the said retort adapted to receive the incandescent charge on its issue from the lower end of the said retort and a receptacle disposed beneath and in line with the said retort whence the charge may be withdrawn, substantially as hereinbefore described.
